UNITED STATES PATENT OFFICE.

FRANK YOKEL, OF CLEVELAND, OHIO, ASSIGNOR TO MARKEL ELECTRIC PRODUCTS, INC., OF BUFFALO, NEW YORK, A CORPORATION OF NEW YORK.

DESIGN FOR A WALL-BRACKET ELECTRIC FIXTURE.

Application filed January 23, 1928. Serial No. 24,986. Term of patent 3½ years.

To all whom it may concern:

Be it known that I, FRANK YOKEL, a citizen of the United States, residing at Cleveland, in the county of Cuyahoga and State of Ohio, have invented a new, original, and ornamental Design for a Wall-Bracket Electric Fixture, of which the following is a specification, reference being had to the accompanying drawing, forming part thereof.

In said drawing:

The figure is a front elevation of a wall bracket electric fixture embodying my new design.

I claim:

The ornamental design for a wall bracket electric fixture, as shown.

FRANK YOKEL.
